UNITED STATES PATENT OFFICE

WILLIAM G. HURLBERT, JR., AND ELMER E. MARSHMAN, OF WARREN, OHIO

EXPANDED METAL LATH

Application filed March 31, 1927. Serial No. 179,852.

Our invention is an improvement in expanded sheet metal such as expanded metal lath, expanded corner beads, expanded metal casings, expanded interior metal trim, and 5 the like.

An object of our invention is to provide a sheet metal structure, having an intermediate unexpanded portion and uniformly expanded side portions.

10 Another object of our invention is to construct metal lath or like structure having its side edges formed to prevent cracking of the plaster bonding an edge of said lath with adjacent edges or an adjacent lath or like structure.

Another object of our invention is to provide a sheet metal structure, having a portion expanded uniformly in the direction of its width and capable of receiving and supporting 20 material such as plaster without danger of such material cracking or becoming loose and falling from the lath.

Other objects of our invention will become 25 more apparent as the following description of several embodiments thereof progresses, reference being made to the accompanying drawings in which like reference characters are employed to designate like parts throughout the same.

30 Figs. 1 and 2 are fragmentary sectional views, showing manners of joining adjacent sheets of lath.

Fig. 3 is a plan view of an embodiment of our invention.

35 Fig. 4 is a transverse section thereof on line 4—4.

Figs. 5 and 6 are fragmentary sectional views, showing manners of joining adjacent sheets of lath.

40 Fig. 7 is a plan view of another embodiment of our invention.

Fig. 8 is a transverse section thereof on the line 8—8.

45 In carrying out our invention we construct a lath comprising a body of suitable material, preferably sheet metal, one or more portions of the body being expanded in the direction of the width of the lath.

50 Referring to Figs. 3, 4, 5 and 6, of the drawings which illustrate an embodiment of

our invention, the lath may be constructed of a sheet of suitable metal comprising a body perforated or slotted longitudinally at intervals as at 7—7' and 8—8', the metal between the slots 7—7' and 8—8', respectively, being 55 formed into truss-loops 9 and 10, respectively. In this embodiment the truss loops are shown as being formed in substantially inverted U-shape cross section. This is illustrated in Fig. 4 at 11. Longitudinal reinforcing ribs 60 4' may be provided between adjacent rows of truss loops as shown. Openings 12 are provided and are bridged longitudinally by the truss loops 9 and 10. The truss-loops of each row are preferably arranged in longitudinal 65 alignment and are preferably staggered relative to the truss-loops of adjacent rows as illustrated in Fig. 3.

We have provided means for preventing 70 cracking of the plaster or other bonding material employed to secure adjacent laths in overlapping edge to edge relation. Such means may consist in forming the metal along the edges of the laths to permit plaster, applied to the overlapping edges, to effectively grip and bond these overlapping edges 75 together over substantially their entire expanded area.

One manner of forming the metal along the 80 edges of the lath may consist in uniformly expanding the said metal in the direction of the width of the lath, such expansion being accomplished by forming substantially parallel rows of slits 13 in the metal adjacent the edge, the slits extending substantially parallel to the side edges of the lath, and stretching and distorting the metal on one side of each of the slits. The rows of slits are arranged 85 preferably in staggered relation. In this manner a portion of the plaster is permitted to key through the slits in the respective lath edges and interlock therewith. The gripping area for the plaster about the overlapping edges is thus materially increased and is distributed uniformly, so that cracking of 90 the plaster about the joint is prevented.

We may provide additional means for binding or securing the adjacent edges of the lath together by applying small wire loops 14 Fig. 6 at intervals along the said edges. 100

Then the adjacent edges of the lath may be secured together in non-overlapping relation, the laths lying in substantially the same plane. When the laths are connected in this manner and plaster is applied the wire loops 14 serve as a reinforcement for the plaster and prevent its cracking about the joint.

Referring to Figs. 7, 8, 1 and 2, we have illustrated another modification of our invention which is similar in some respects to that form shown in Figs. 3, 4, 5, and 6. However, it will be noted that in the present embodiment we have formed the perforated portion of the lath by slitting the same longitudinally at intervals as at 20 and crimp the metal intermediate adjacent the slits to form truss-loops 21. The loops thus formed are arranged in rows, the loops of one row being preferably in staggered relation to the loops of adjacent rows. The metal intermediate each row is ribbed longitudinally as at 22. In this form of our invention we form the truss-loops by slitting the body of the lath longitudinally in substantially parallel rows 23 and then crimping or bending the metal between the respective slits of certain of the rows so that the edges of the loops 24 extend outwardly of the loops, while the intermediate portions 25 are slightly concaved.

We have also provided means for preventing cracking of the plaster or other bonding material employed to secure adjacent laths in overlapped edge-to-edge relation. Such means is similar to that described in connection with the embodiment illustrated in Figs. 3, 4, 5 and 6, and consists in slitting the metal adjacent the edges of the lath as at 26 the slits being arranged in longitudinal rows, while the slits of one row are preferably staggered with respect to slits of adjacent rows. The metal on one side of each slit is distorted as at 27 to laterally expand the metal along the longitudinal edges of the lath.

Although we have shown and described herein certain of the ribs 4' and 22 formed adjacent the expanded edge portions of the respective laths, it is to be understood that we may dispense with those ribs adjacent the expanded portions, and may form the truss loops adjacent these edges with no intervening ribbed structure.

Various changes may be made in the details of construction of our invention without departing from the spirit of the invention or the scope of the subjoined claims.

What we claim is:

1. A metal lath including a body having an intermediate perforated portion and expanded edge portions, said intermediate portion having pairs of openings therein arranged in longitudinal parallel rows, the portions between each pair of openings being deformed out of the plane of the body, said deformed portions being of a substantial curvi-linear transverse section.

2. A metal lath including a body having an intermediate perforated portion and expanded edge portions, said intermediate portion having pairs of openings therein arranged in longitudinal parallel rows, the portions between each pair of openings being deformed out of the plane of the body, said deformed portions being of a substantial curvi-linear transverse section, and longitudinal ribs separating one of the parallel rows of openings from adjacent parallel rows of openings.

3. A metal lath including a body having an intermediate perforated portion and expanded edge portions, said intermediate portion having pairs of openings therein arranged in longitudinal parallel rows, the portions between each pair of openings being deformed out of the plane of the body, and being deformed to a greater extent at the edges than at its intermediate portion, the longitudinal edges of the lath being slitted and expanded laterally.

4. A metal lath including a body having an intermediate perforated portion and expanded edge portions, said intermediate portion having pairs of openings therein arranged in longitudinal parallel rows, the portions between each pair of openings being deformed out of the plane of the body, and being deformed to a greater extent at the edges than at its intermediate portion, and longitudinal ribs separating one of the parallel rows of openings from adjacent parallel rows of openings, the longitudinal edges of the lath being slitted and expanded laterally.

5. A metal lath comprising a body having an unexpanded central portion, perforated and expanded marginal portions, said unexpanded central portion having a longitudinal reinforcing rib disposed within the horizontal planes bounding the expanded portions.

6. A metal lath comprising a body having an unexpanded central portion, perforated and uniformly expanded marginal portions, said unexpanded central portion having a longitudinal reinforcing rib disposed within the horizontal planes bounding the expanded portions.

7. A metal lath comprising a body having a perforated unexpanded central portion, perforated and expanded marginal portions, longitudinal reinforcing ribs in said central portion, said ribs being disposed within the horizontal plane bounding the crest of the expanded marginal portions.

8. A metal lath comprising a body having a perforated unexpanded central portion, longitudinal reinforcing ribs in said portion, marginal perforated portions distorted and constituting open meshwork, said longitudinal ribs lying a medial plane of said open mesh work.

9. A metal lath comprising a body having a perforated unexpanded central portion, longitudinal reinforcing ribs in said portion, marginal perforated portions distorted uniformly and constituting open meshwork, said longitudinal ribs lying in a medial plane of said open meshwork.

5 10. A metal lath including a body having a central perforated portion and perforated and expanded edge portions, said central portion having pairs of openings therein arranged in longitudinal rows, the portions between each pair of openings being deformed out of the plane of the body, the deformed portions being of a substantial arcuate transverse section.

15 20. 11. A metal lath including a body having a central perforated portion and perforated and expanded edge portions, said central portion having pairs of openings therein arranged in longitudinal rows, the portions between each pair of openings being deformed out of the plane of the body, the deformed portions being of a substantial arcuate transverse section, and longitudinal ribs disposed in spaced relation with the said parallel rows of openings.

25 30. 35. 12. A metal lath including a body having a central perforated portion and perforated expanded edge portions, the central portion having portions arranged in parallel rows deformed out of the plane of the body, said deformed portions having an arcuated crest with divergent sides, defining pairs of openings and longitudinal ribs interjacent the said rows of deformations.

In testimony whereof we hereunto affix our signatures this 1st day of March, 1927.
